Primary Examiner—Terry A Wallace(74) *Attorney, Agent, or Firm*—Gary L. Bush; Andrew Kurth LLP(57) **CLAIM**

The ornamental design for a cooking spoon, as shown and described.

DESCRIPTION

FIG. 1 is a perspective view of a cooking spoon showing our new design;

FIG. 2 is a front view thereof;

FIG. 3 is a side view thereof;

FIG. 4 is a bottom view thereof;

FIG. 5 is a top view thereof;

FIG. 6 is a cross-sectional view thereof taken along line 6—6 of FIG. 2; and,

FIG. 7 is a cross-sectional view thereof taken along line 7—7 of FIG. 2.

The broken lines in FIG. 1 show a handle connected to the cooking spoon, are for illustrative purposes only, and form no part of the claimed design. The handle has been omitted from FIGS. 2-7, which show only the claimed design.
